UNITED STATES PATENT OFFICE.

JOSEPH VESELY, OF UNION CITY, PENNSYLVANIA.

SPINNING MACHINE.

Application filed September 27, 1923, Serial No. 665,124. Renewed October 2, 1924.

To all whom it may concern:

Be it known that I, JOSEPH VESELY, a citizen of Czechoslovakia, residing at Union City, in the county of Erie and State of Pennsylvania, have invented certain new and useful Improvements in Spinning Machines, of which the following is a specification.

This invention relates to the art of spinning, and has special reference to a machine for spinning cordage such as twines, small ropes and the like.

More particularly the invention relates to a machine for spinning cordage from several strands of fibrous material either like or unlike in kind and texture.

One important object of the invention is to improve the general construction of devices of this character.

20 A second important object of the invention is to provide an improved form of spinning machine wherein the spun material will be wound on a spindle or bobbin as fast as it is spun.

25 A third important object of the invention is to provide an improved form of spinning machine wherein novel provision will be made for the formation of a sliver from fibrous material and then spinning the same.

30 A fourth important object of the invention is to provide for spinning several strands together, certain of which are twisted in one direction and the remainder of which are twisted in the opposite direction.

With the above and other objects in view as will be hereinafter apparent, the invention consists in general of certain novel details of construction and combinations of parts hereinafter more fully described, illustrated in the accompanying drawings and specifically claimed.

In the accompanying drawings like characters of reference indicate like parts in the several views, and:

Fig. 1 is a front elevation of the machine as installed on a sewing machine stand.

Fig. 2 is an enlarged side elevation of the machine partly in section.

50 Fig. 3 is a section on the line III—III of Fig. 2.

Fig. 4 is a section on the line IV—IV of Fig. 2.

Fig. 5 is an enlarged section on the line V—V of Fig. 4.

Fig. 6 is an enlarged section on the line VI—VI of Fig. 4.

Fig. 7 is an enlarged section on the line VII—VII of Fig. 2.

Fig. 8 is an enlarged section on the line VIII—VIII of Fig. 2.

Fig. 9 is an enlarged section through the sliver forming rolls.

In the embodiment of the invention herein disclosed, there is provided a base 10 whereon are arranged spaced standards 11 and 12. Journalled in the standard 11 is a tubular shaft 13, this shaft being also journalled in a standard 14 placed adjacent said standard 11. Fixed on the shaft 13 between the standards 11 and 14 is a grooved pulley 15 which is connected by a belt 16 to the driving wheel 17 of a sewing machine, the latter being driven in the usual manner by a pedal 18 and connecting rod 19. Fixed in the standard 12 is a tubular shaft 20.

Between the standards 11 and 12 is located what is preferably termed a flyer frame consisting of the heads 21 and 22 and the connecting bars 23. The head 21 is fixed on the shaft 13 to revolve therewith while the shaft 20 forms a journal on which is revolubly mounted the head 22. In this head 22 is a recess 24 and fixed on the shaft in this recess is a grooved pulley 25 connected by a belt 26 with a similar grooved pulley 27 mounted on a worm shaft 28 journalled in the head 22. Extending between the heads 21 and 22 is a pair of frame members 29 between which is journalled a worm wheel 30 meshing with a worm 31 on the shaft 28. The worm wheel 30 constitutes a crank disk which is connected by a link 32 with a guide lever 33 having a guide eye 34 in its free end.

Slidably mounted in a recess 35 in the head 21 is a bearing 36 which is constantly urged outward by a spring 37. This bearing receives one journal end of a spindle or bobbin 38, the other journal end being received in a suitable bearing recess in the head 22 and the spindle being provided near its last mentioned end with a grooved pulley 39 connected by a belt 40 with a grooved pulley 41 fixed on the inner end of the shaft 20.

Spaced from the standard 12 is a pair of spaced standards 42 provided with suitable

bearings 43 for the reception of the journal ends of spindles or bobbins 44 on which are wound the loosely twisted strands or slivers 45. These strands 45 are passed through the 5 tubular shaft 20 and thence through the eye 34 to the bobbin or spindle 28. As the flyer head rotates by the action of the belt 16 the strands are twisted together between the eye 34 and the shaft 20. Furthermore, the 10 worm will be rotated during the rotation of the flyer frame by means of the pulleys 24 and 26 and belt 25 so that the worm wheel will rotate and move the lever to and fro along the bobbin 38 which also rotates on its 15 axis through the action of the pulleys 39 and 41 and belt 40. Thus the strands will be twisted together and wound in even layers on the bobbin 38.

Adjacent the standard 14 is a bin 46 for 20 the reception of fibrous material 47, a picker 48 being mounted at the top of the bin to pick and loosen the said material as it is deposited in the bin. This picker is mounted on a shaft 49 carrying a grooved pulley 50 connected by a belt 51 with a pulley 52 on the shaft 13 so that rotation of this shaft effects rotation of said picker. Adjacent the bottom of the bin is an opening 53 at the sides of which are standards 54 carrying 30 rollers 55. In the operation of this part of the device the fibrous material is pulled out of the opening and passed between the rollers 55 from whence it passes through the tubular shaft 13, and then through the eye 34 to the bobbin 38. It will be observed 35 that the strand 56 formed from this material is twisted in the opposite direction to the twist of the strands 45.

It is obvious that the spring bearing support of the bobbin permits removal of the bobbin when filled and its replacement by an empty bobbin.

There has thus been provided a simple and efficient device of the kind described and for 45 the purpose specified.

It is obvious that minor changes may be made in the form and construction of the invention without in any way departing from the material spirit thereof. It is not, therefore desired to confine the invention to the exact form herein shown and described, but it is wished to include all such as properly come within the scope claimed.

Having thus described the invention, what is claimed as new, is:

1. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the flyer frame through the hollow shaft, a bobbin eccen-

trically supported in the flyer frame for revolution therein, means to rotate the flyer frame, a lever oscillatably mounted in said flyer frame and having a guide eye through which the fibrous strand may pass for winding on the bobbin, means to revolve said bobbin, and means to oscillate said lever. 70

2. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the 80 flyer frame through the hollow shaft, a bobbin eccentrically supported in the flyer frame for revolution therein, means to rotate the flyer frame, a lever oscillatably mounted in said flyer frame and having a guide eye through which the fibrous strand 85 may pass for winding on the bobbin, a pulley on said bobbin, a pulley on the fixed shaft, a belt connecting said pulleys, and means to oscillate said lever. 90

3. The combination with a supporting frame of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the 100 flyer frame through the hollow shaft, a bobbin eccentrically supported in the flyer frame for revolution therein, means to rotate the flyer frame, a lever oscillatably mounted in said flyer frame and having a guide eye through which the fibrous strand 105 may pass for winding on the bobbin, a pulley on said bobbin, a pulley on the fixed shaft, a belt connecting said pulleys, and means to oscillate said lever. 110

4. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the 115 flyer frame through the hollow shaft, a bobbin eccentrically supported in the flyer frame for revolution therein, means to rotate the flyer frame, a lever oscillatably mounted in said flyer frame and having a guide eye through which the fibrous strand 120 may pass for winding on the bobbin, a worm shaft carrying a worm and journaled in said flyer frame, a pulley on said worm shaft, a second pulley on the fixed shaft, a belt connecting the second pulley and the worm shaft pulley, a worm wheel journaled in said flyer frame and meshing with said worm, said worm wheel constituting a crank disk, and a link connecting the worm wheel and lever. 125

5. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the 130 flyer frame through the hollow shaft, a bobbin eccentrically supported in the flyer frame for revolution therein, means to rotate the flyer frame, a lever oscillatably mounted in said flyer frame and having a guide eye

through which the fibrous strand may pass for winding on the bobbin, a belt connecting said pulleys, a worm shaft carrying a worm and journalled in said flyer frame, a pulley 5 on said worm shaft, a second pulley on the fixed shaft, a belt connecting the second pulley and the worm shaft pulley, a worm wheel journalled in said flyer frame and meshing with said worm, said worm wheel constituting 10 a crank disk, and a link connecting the worm wheel and lever.

5. The combination with a supporting frame; of a pair of alined shafts mounted in said frame, one of said shafts being journalled 15 in the frame and the second shaft being fixed in said frame, a flyer frame fixed at one end to the first shaft and revolubly supported on the second shaft, one of said shafts forming a tubular guide, means to supply a 20 strand of fibrous material to the flyer frame through the hollow shaft, a bobbin eccentrically supported in the flyer frame for revolution therein, means to rotate the flyer frame, a lever oscillatably mounted in said flyer 25 frame and having a guide eye through which the fibrous strand may pass for winding on the bobbin, means to revolve said bobbin, means to oscillate said lever, said second shaft being also hollow to constitute a tubular 30 guide, and means to supply a strand of fibrous material to the flyer frame through the second shaft, the guide eye forming a guide through which the last mentioned strand may pass on its way to the bobbin.

35 6. The combination with a supporting frame; of a pair of alined shafts mounted in said frame, one of said shafts being journalled in the frame and the second shaft being fixed in said frame, a flyer frame fixed 40 at one end to the first shaft and revolubly supported on the second shaft, one of said shafts forming a tubular guide, means to supply a strand of fibrous material to the 45 flyer frame through the hollow shaft, a bobbin eccentrically supported in the flyer frame for revolution therein, means to rotate the flyer frame, a lever oscillatably mounted in said flyer frame and having a guide eye 50 through which the fibrous strand may pass for winding on the bobbin, a pulley on said bobbin, a pulley on the fixed shaft, a belt connecting 55 said pulleys, a worm shaft carrying a worm and journalled in said flyer frame, a pulley on said worm shaft, a second pulley on the fixed shaft, a belt connecting the second pulley and the worm shaft pulley, a worm wheel journalled in said flyer frame and meshing with said worm, said worm wheel constituting 60 a crank disk, a link connecting the worm wheel and lever, said second shaft being also hollow to constitute a tubular guide, and means to supply a strand of fibrous material to the flyer frame through the second shaft, the guide eye forming a guide through which the last mentioned strand may pass on its way to the bobbin.

60 7. The combination with a supporting frame; of a pair of alined shafts mounted in said frame, one of said shafts being journalled in the frame and the second shaft being fixed in said frame, a flyer frame fixed 65 at one end to the first shaft and revolubly

supported on the second shaft, one of said shafts forming a tubular guide, means to supply a strand of fibrous material to the flyer frame through the hollow shaft, a bobbin eccentrically supported in the flyer frame 70 for revolution therein, means to rotate the flyer frame, a lever oscillatably mounted in said flyer frame, and having a guide eye through which the fibrous strand may pass for winding on the bobbin, means to revolve 75 said bobbin, a worm shaft carrying a worm and journalled in said flyer frame, a pulley on said worm shaft, a second pulley on the fixed shaft, a belt connecting the second pulley and the worm shaft pulley, a worm wheel 80 journalled in said flyer frame and meshing with said worm, said worm wheel constituting a crank disk, a link connecting the worm wheel and lever, said second shaft being also hollow to constitute a tubular guide, and means to supply a strand of fibrous material to the 85 flyer frame through the second shaft, the guide eye forming a guide through which the last mentioned strand may pass on its way to the bobbin.

90 8. The combination with a supporting frame; of a pair of alined shafts mounted in said frame, one of said shafts being journalled in the frame and the second shaft being fixed in said frame, a flyer frame fixed 95 at one end to the first shaft and revolubly supported on the second shaft, one of said shafts forming a tubular guide, means to supply a strand of fibrous material to the flyer frame through the hollow shaft, a bobbin eccentrically supported in the flyer frame for revolution therein, means to rotate the flyer frame, a lever oscillatably mounted in said flyer frame and having a guide eye 100 through which the fibrous strand may pass for winding on the bobbin, a belt connecting said pulleys, a worm shaft carrying a worm and journalled in said flyer frame, a pulley on said worm shaft, a second pulley on the fixed shaft, a belt connecting the second pulley and the worm shaft pulley, a worm wheel journalled in said flyer frame and meshing with said worm, said worm wheel constituting 105 a crank disk, a link connecting the worm wheel and lever, said second shaft being also hollow to constitute a tubular guide, and means to supply a strand of fibrous material to the flyer frame through the second shaft, the guide eye forming a guide through which the last mentioned strand may pass on its 110 way to the bobbin.

115 9. The combination with a supporting frame; of a pair of alined shafts mounted in said frame, one of said shafts being journalled in the frame and the second shaft being fixed in said frame, a flyer frame fixed 120 at one end to the first shaft and revolubly supported on the second shaft, one of said shafts forming a tubular guide, means to supply a strand of fibrous material to the 125 flyer frame through the second shaft, the

flyer frame through the hollow shaft, a bobbin eccentrically supported in the flyer frame for revolution therein, means to rotate the flyer frame, a lever oscillatably mounted in said flyer frame and having a guide eye through which the fibrous strand may pass for winding on the bobbin, means to revolve said bobbin, means to oscillate said lever, said second shaft being also hollow to constitute a tubular guide, a bin adjacent said second shaft for the reception of loose fibrous material and having an opening near its bottom, and a pair of rollers adjacent the opening through which loosely compacted material may pass from the opening to the second shaft and through that shaft and the guide eye to the bobbin.

10. The combination with a supporting frame; of a pair of alined shafts mounted in said frame, one of said shafts being journaled in the frame and the second shaft being fixed in said frame, a flyer frame fixed at one end to the first shaft and revolvably supported in the second shaft, one of said shafts forming a tubular guide, means to supply a strand of fibrous material to the flyer frame through the hollow shaft, a bobbin eccentrically supported in the flyer frame for revolution therein, means to rotate the flyer frame, a lever oscillatably mounted in said flyer frame and having a guide eye through which the fibrous strand may pass for winding on the bobbin, means to revolve said bobbin, a worm shaft carrying a worm and journaled in said flyer frame, a pulley on said worm shaft, a second pulley on the fixed shaft, a belt connecting the second pulley and the worm shaft pulley, a worm wheel journaled in said flyer frame and meshing with said worm, said worm wheel constituting a crank disk, a link connecting the worm wheel and lever, said second shaft being also hollow to constitute a tubular guide, a bin adjacent said second shaft for the reception of loose fibrous material and having an opening near its bottom, and a pair of rollers adjacent the opening through which loosely compacted material may pass from the opening to the second shaft and through that shaft and the guide eye to the bobbin.

11. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the flyer frame through the hollow shaft, a bobbin eccentrically supported in the flyer frame for revolution therein, means to rotate the flyer frame, a lever oscillatably mounted in said flyer frame and having a guide eye through which the fibrous strand may pass for winding on the bobbin, a pulley on said bobbin, a pulley on the fixed shaft, a belt connecting said pulleys, a worm shaft carrying a worm and journaled in said flyer frame, a pulley on said worm shaft, a second pulley on the fixed shaft, a belt connecting the second pulley and the worm shaft pulley, a worm wheel journaled in said flyer frame and meshing with said worm, said worm wheel constituting a crank disk, a link con-

a bin adjacent said second shaft for the reception of loose fibrous material and having an opening near its bottom, and a pair of rollers adjacent the opening through which loosely compacted material may pass from the opening to the second shaft and through that shaft and the guide eye to the bobbin.

12. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the flyer frame through the hollow shaft, a bobbin eccentrically supported in the flyer frame for revolution therein, means to rotate the flyer frame, a lever oscillatably mounted in said flyer frame and having a guide eye through which the fibrous strand may pass for winding on the bobbin, means to revolve said bobbin, a worm shaft carrying a worm and journaled in said flyer frame, a pulley on said worm shaft, a second pulley on the fixed shaft, a belt connecting the second pulley and the worm shaft pulley, a worm wheel journaled in said flyer frame and meshing with said worm, said worm wheel constituting a crank disk, a link connecting the worm wheel and lever, said second shaft being also hollow to constitute a tubular guide, a bin adjacent said second shaft for the reception of loose fibrous material and having an opening near its bottom, and a pair of rollers adjacent the opening through which loosely compacted material may pass from the opening to the second shaft and through that shaft and the guide eye to the bobbin.

13. The combination with a supporting frame; of a pair of alined shafts mounted in said frame, one of said shafts being journaled in the frame and the second shaft being fixed in said frame, a flyer frame fixed at one end to the first shaft and revolvably supported on the second shaft, one of said shafts forming a tubular guide, means to supply a strand of fibrous material to the flyer frame through the hollow shaft, a bobbin eccentrically supported on the flyer frame for revolution therein, means to rotate the flyer frame, a lever oscillatably mounted in said flyer frame and having a guide eye through which the fibrous strand may pass for winding on the bobbin, a belt connecting said pulleys, a worm shaft carrying a worm and journaled in said flyer frame, a pulley on said worm shaft, a second pulley on the fixed shaft, a belt connecting the second pulley and the worm shaft pulley, a worm wheel journaled in said flyer frame and meshing with said worm, said worm wheel constituting a crank disk, a link con-

necting the worm wheel and lever, said second shaft being also hollow to constitute a tubular guide, a bin adjacent said second shaft for the reception of loose fibrous material and having an opening near its bottom, and a pair of rollers adjacent the opening through which loosely compacted material may pass from the opening to the second shaft and through that shaft and the 10 guide eye to the bobbin.

14. The combination with a supporting frame; of a pair of alined shafts mounted in said frame, one of said shafts being journaled in the frame and the second shaft 15 being fixed in said frame, a flyer frame fixed at one end to the first shaft and revolubly supported on the second shaft, one of said shafts forming a tubular guide, means to supply a strand of fibrous material to the 20 flyer frame through the hollow shaft, a bobbin eccentrically supported in the flyer frame for revolution therein, means to rotate the flyer frame, a lever oscillatably mounted in said flyer frame and having a guide eye 25 through which the fibrous strand may pass for winding on the bobbin, a pulley on said bobbin, a pulley on the fixed shaft, a belt connecting said pulleys, means to oscillate said lever, a bin adjacent said second shaft for 30 the reception of loose fibrous material and having an opening near its bottom, and a picker on said bin operated by the second shaft.

15. The combination with a supporting frame; of a pair of alined shafts mounted in said frame, one of said shafts being journaled in the frame and the second shaft 35 being fixed in said frame, a flyer frame fixed at one end to the first shaft and revolubly supported on the second shaft, one of said 40 shafts forming a tubular guide, means to supply a strand of fibrous material to the flyer frame through the hollow shaft, a bobbin eccentrically supported in the flyer 45 frame for revolution therein, means to rotate the flyer frame, a lever oscillatably mounted in said flyer frame and having a guide eye

through which the fibrous strand may pass for winding on the bobbin, means to revolve said bobbin, a worm shaft carrying a worm 50 and journalled in said flyer frame, a pulley on said worm shaft, a second pulley on the fixed shaft, a belt connecting the second pulley and the worm shaft pulley, a worm wheel journalled in said flyer frame and 55 meshing with said worm, said worm wheel constituting a crank disk, a link connecting the worm wheel and lever, a bin adjacent 60 said second shaft for the reception of loose fibrous material and having an opening near its bottom, and a picker on said bin operated by the second shaft.

16. The combination with a supporting frame; of a pair of alined shafts mounted in said frame, one of said shafts being journaled in the frame and the second shaft being fixed in said frame, a flyer frame fixed at one end to the first shaft and revolubly supported on the second shaft, one of said shafts forming a tubular guide, means to 70 supply a strand of fibrous material to the flyer frame through the hollow shaft, a bobbin eccentrically supported in the flyer frame for revolution therein, means to rotate the flyer frame, a lever oscillatably mounted in said flyer frame and having a guide eye 75 through which the fibrous strand may pass for winding on the bobbin, a belt connecting said pulleys, a worm shaft carrying a worm and journalled in said flyer frame, a pulley on 80 said worm shaft, a second pulley on the fixed shaft, a belt connecting the second pulley and the worm shaft pulley, a worm wheel journalled in said flyer frame and meshing with 85 said worm, said worm wheel constituting a crank disk, a link connecting the worm wheel and lever, a bin adjacent said second shaft for the reception of loose fibrous material and having an opening near its bottom, and a picker on said bin operated by 90 the second shaft.

In testimony whereof I affix my signature.

JOSEPH VESELY.
